HEMMING ATTACHMENT FOR AUTOMATIC FEEDING AND SEWING MACHINES

Henry Gensheimer, New York, N. Y.

Application April 9, 1945, Serial No. 587,286

6 Claims. (Cl. 112—141)

1

This invention relates to new and useful improvements in a hemming attachment for an automatic feeding and sewing machine.

More specifically, the invention proposes the provision of a folding member used in conjunction with a transverse folding bar for forming a transverse fold in a moving web of cloth material. It is also proposed to provide a transverse guide rod beneath and to the back of said folding bar for guiding said cloth web to said bar.

The invention proposes to characterize the folding member by the fact that it is mounted upon one end of said transverse folding bar and acts to fold, or bend a longitudinal edge portion of said moving web upon the remaining portion of the web.

It is proposed to so construct the folding member that it may be shifted slightly on said folding bar to better control the folding operation.

The folding member is arranged with a base wall having a bottom flange bent inwards from the front edge thereof and covering the front edge of the folding bar at one end. Said base wall has its outer end continuing into an end curved portion which continues into an overhanging top portion upon which an internal bending portion is mounted for forming a longitudinal edge fold. It is proposed that the bottom flange of said folding member continue over said overhanging portion which assists in reversing and bending the edge portion on the moving web to form the fold.

The folded edge portion as formed by this hemming attachment may then be guided to a sewing machine which automatically sews it down.

Still further this invention proposes the construction of a hemming attachment as briefly described which is simple, efficient in operation, and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a hemming attachment constructed in accordance with this invention, to which a moving web has been schematically added.

Fig. 2 is a plan view of the folding member of the hemming attachment, illustrated per se.

Fig. 3 is a bottom view of Fig. 2.

2

Fig. 4 is a side elevational view looking in the direction of the line 4—4 of Fig. 2.

Fig. 5 is a front elevational view of the folding member looking in the direction of the line 5—5 of Fig. 2.

Fig. 6 is a rear elevational view of Fig. 5.

Fig. 7 is a fragmentary plan view of the hemming attachment applied to an automatic sewing machine in accordance with this invention.

10 Fig. 8 is an enlarged vertical sectional view taken on the line 8—8 of Fig. 2.

Fig. 9 is a fragmentary enlarged vertical sectional view taken on the line 9—9 of Fig. 7.

15 Fig. 10 is a fragmentary schematic plan view similar to Fig. 2 but illustrating the first step in applying the cloth web to the folding member.

Fig. 11 is a fragmentary view similar to Fig. 1 but showing the moving web fully applied.

The hemming attachment in accordance with 20 this invention, includes a transverse folding bar 15 for forming a transverse fold 16 in a moving web of cloth material 17. A transverse guide rod 18 is located beneath and to the back of the front edge of said transverse folding bar 15 for guiding said cloth web to said bar 15. A folding member 20 is mounted upon one end of said folding bar 15. This folding member 20 has a base wall 21 provided with a bottom flange 22 which is bent rearwards from the front edge thereof and which 25 covers the front edge of said folding bar 15 at one end of the folding bar 15. The folding bar 15 and the guide rod 18 are of a relatively great length so that wide webs of cloth material may 30 have their edges folded with the hemming attachment. For example, the bar 15 and rod 18 may be as of a sufficient length so that window 35 curtains may be hemmed with the instant hemming attachment.

The base wall 21 has its outer end continuing 40 into a curved end portion 24 which continues into an overhanging portion 25. The bottom flange 22 continues at one end into an overhanging top portion 26 which is triangularly shaped and forms a bending or reversing portion. This triangular shape top portion 26 may be clearly seen in Figs. 1 and 2. The back edge of the triangular shape top portion 26 is provided with a guiding lip 27 against which the edge of the web engages and 45 is guided.

An internal bending portion 28 is mounted 50 within the overhanging top portion 25 for forming an edge fold 29 longitudinal along one edge of said moving web 17. Said overhanging portion 25 continues from the overhanging top por-

tion 26 into a bent edge, or junction 30 of these parts.

The internal bending portion 28 consists of a wall portion 34 spaced slightly above the base wall 21 and continuing into a curved end portion 35 spaced slightly inwards from the curved end portion 24 of the base wall 21, and said curved end portion 35 continuing into an overhanging portion 36 spaced slightly downwards of the overhanging portion 25. The edge 37 of the overhanging portion 36 is connected with and attached to the curved edge 38 of the junction of the overhanging portions 25 and 36 by which the internal bending portion 28 is supported. With this construction there is a space 40 through which the fold 29 of the moving web 17 passes, and by which the edge fold 29 is formed.

A lug 41 is secured to the side of the curved end portion 24 by which the folding member 20 is attached to the folding bar 15. This lug 41 is provided with a transverse slot 42 through which a clamping screw 43 is engaged. This clamping screw 43 is mounted upon the end of the folding bar 15.

The operation of the hemming attachment may be understood from the following:

Fig. 10 should first be studied, and it should be noted that the edge fold 29 is freely passing through the space 40. The moving web 17 is free to move through the folding member 20 in this condition. However, when the hemming attachment is working, the parts are in the condition shown in Fig. 11 and to place the web 17 in this position, it is necessary that that portion of the fold 29 to the front of the triangularly shaped bending and reversing portion 26 to be folded laterally with the edge A of the fold 29 engaging beneath the guiding lip so that that portion of the fold 29 which is over the bending and reversing portion 26 is opened up and folded down, so that we produce the transverse fold 16 extended across the bend of the flange 22 and also extended across the front edge of the folding bar 15.

The bottom portion of the web 17 is guided behind the transverse guide rod 18, and now the web is ready to move. The mechanism for moving the web is not shown in this application since it forms no part of the invention. The web 17 is intended to move in the direction indicated by the arrow B. It is intended that the web 17 have its folded edge portion 29 engaged through a guide C, see Fig. 7, and then beneath the needles of the twin needle sewing machine D. With this arrangement the sewing machine D may operate continuously and the moving web 17 will have its edge folded and sewed down. In this way the web 17 is formed with a hem.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base

70 75

wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said moving web.

2. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said moving web.

3. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said moving web, the end portion of said transverse folding bar being clamped in between said base wall and said bottom flange.

4. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said

moving web, the end portion of said transverse folding bar being clamped in between said base wall and said bottom flange, a lug fixedly mounted on said curved end portion of said base wall, and means for fixedly connecting said lug with said folding bar, comprising a clamp screw mounted upon said folding bar and passing through an elongated slot formed in said lug.

5. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said moving web, the end portion of said transverse folding bar being clamped in between said base wall and said bottom flange, a lug fixedly mounted on said curved end portion of said base wall, and means for fixedly connecting said lug with said folding bar, comprising a clamp screw mounted upon said folding bar and passing through an elongated slot formed in said lug, said slot being longitudinal of the length of said folding bar.

6. A compact two way hemming attachment, comprising a transverse folding bar for forming a transverse fold in a moving web of cloth material, a transverse guide rod beneath said folding bar for guiding said cloth web to said bar, and adjacent thereto a folding member mounted on one end of said folding bar and having a base wall with a bottom flange bent rearwards from the front edge thereof and covering the front edge of said folding bar at one end, said base wall having its outer end continuing into an end curved portion which continues into an overhanging top portion and said bottom flange continuing over said overhanging top portion into a triangularly shaped bending and reversing portion, and an internal bending portion mounted within said overhanging top portion for forming an edge fold longitudinally along one edge of said moving web, said triangularly shaped bending and reversing portion having a guiding lip upon this rear edge for guiding the edge of said moving web.
